UNITED STATES PATENT OFFICE.

ALVA HEYWOOD COOPER, OF ATLANTA, GEORGIA.

BLOW-OUT SHOE.

Application filed February 14, 1925. Serial No. 9,253.

To all whom it may concern:

Be it known that I, ALVA H. COOPER, a citizen of the United States, residing at Atlanta, in the county of Fulton and State 55
5 of Georgia, have invented a new and useful Blow-Out Shoe, of which the following is a specification.

The device forming the subject matter of this application is a blow-out shoe, adapted 10 to be placed within the casing of a vehicle tire, and the invention aims to provide a structure of the kind described which will be so made that it will withstand severe use.

It is within the province of the disclosure 15 to improve generally and to enhance the utility of devices of that sort to which the invention appertains.

Although a preferred form of the invention has been shown, it will be understood 20 that a mechanic, working within the scope of what is claimed, may make changes and alterations without departing from the spirit of the invention.

In the accompanying drawings:—

25 Figure 1 shows in top plan, a device constructed in accordance with the invention; Figure 2 is a bottom plan wherein parts are broken away; and Figure 3 is a cross section wherein the shoe is shown disposed in 30 trough-shape.

The blow-out shoe forming the subject matter of this application is made of textile material, preferably heavy raw canvas. The shoe comprises a body 1. The length 2 of 35 the body 1 is greater than the width of the body. A plurality of layers 4, 5 and 6 are superposed on the body 1. The area of each of the layers 4, 5 and 6 is less than the area of the layer next therebeneath. The 40 area of the innermost layer 4 is less than the area of the body 1.

The device comprises a zig-zag stitching 7. The stitching 7 is composed of long parallel parts 8 and short parallel parts 9. The 45 parts 9 of the stitching connect the parts 8 at the ends thereof. The short parts 9 of the stitching are located at right angles to the long parts 8. The short parts 9 of the stitching join innermost layer 4 to the 50 body 1. All of the long parts 9 of the stitching join at least one of the layers

4—5—6 to the body 1. Some of the long parts 8 join all of the layers 4—5—6 to the body 1.

The short parts 9 of the stitching 7 extend 55 parallel to the ends of the body 1 and are spaced apart transversely of the body, as shown at 10. The long parts 8 of the stitching 7 extend parallel to the edges of the body. 60

Owing to the way that the stitching 7 is made and placed, the body 1 and the layers 4—5—6 may be stitched together whilst they are flat, nevertheless, when the shoe is disposed in trough-shape, as shown at 11 in 65 Figure 3, neither the body 1 nor any one of the layers 4, 5 and 6 will crinkle or buckle.

Having thus described the invention, what is claimed is:—

A blow-out shoe for vehicle tires, the shoe 70 being made of textile material and comprising a body, the length of which is greater than its width, a plurality of layers superposed on the body, the area of each layer being less than the area of the layer next 75 therebeneath, the area of the innermost layer being less than the area of the body, and a zig-zag stitching comprising parallel long parts and parallel short parts connecting the long parts at the ends thereof, 80 the short parts being located at right angles to the long parts, the short parts joining the innermost layer to the body, all of the long parts joining at least one of the layers to the body, some of the long parts joining 85 all of the layers to the body; the short parts of the stitching extending parallel to the ends of the body and being spaced apart transversely of the body and the long parts of the stitching extending parallel to the 90 edges of the body thereby permitting the body and the layers to be united by the stitching whilst they are flat and preventing them from buckling when the shoe is disposed in trough shape. 95

In testimony that I claim the foregoing as my own, I have hereto affixed my signature in the presence of two witnesses.

ALVA HEYWOOD COOPER.

Witnesses:

S. T. ALLEN,
FRED F. EDWARDS.
